TEODORO LARREY AND LUIS GODARD, OF MEXICO CITY, MEXICO.

STEAM SUPERHEATING SYSTEM.

Application filed April 4, 1927, Serial No. 180,923, and in Mexico December 27, 1926.

This invention relates to steam superheating systems, designed primarily for installation in locomotives though not limited to that particular application.

5 It involves certain improvements, all fully described hereinafter, in or associated with the construction of the superheating deflector or header which controls the passage of the steam from the dry pipe or pipes to the superheating units disposed within the fire tubes or flues, the construction of the aforesaid superheating units themselves, and the provision of a special head for the deflector which is located between the dry pipe or pipes and 10 the deflector and to which the cylinder supply pipes are also connected.

Further improvements also reside in the special valve employed to control the passage of the superheated steam from the deflector to the cylinder supply pipes, and which is constructed to permit the steam to pass through it, when in closed position, to a chamber located above it in the deflector so as to 15 balance the pressure of the steam beneath it.

20 The deflector head is constructed in a manner to direct the incoming saturated steam to the deflector and to receive the superheated steam from the latter and direct it to the above-mentioned supply pipes; and the deflector itself is made in sections which are 25 detachable individually from the deflector and from the head and other parts or members which support them. The individual superheating units, in like manner, can be 30 disconnected from the deflector and withdrawn from the flues, and they are so shaped as to increase the surface area exposed to the heat in the flues while, at the same time, reducing the volume of steam submitted to 35 such heating, so that superheating takes place in an extremely rapid and effective manner.

40 Other and further advantages and improvements will be explained in the course of the description which follows.

45 In the accompanying drawing:

Figure 1 is a transverse section of a locomotive smoke-box equipped with the present invention;

Fig. 2 is a central vertical section thereof;

50 Fig. 3 is an enlarged cross-section of the front end of one of the superheating units taken on line 3-3, Fig. 2;

Fig. 4 is a fragmental vertical section of the rear end of the superheating unit;

55 Fig. 5 is a plan view of one of the deflector sections;

Fig. 6 is an enlarged vertical sectional view of a three-chamber deflector.

Referring to Figs. 1 and 2, 1 indicates the smoke-box of the steam engine or locomotive, 60 2 the boiler wall, 3 the tube sheet and 4 the fire tubes or flues. The dry pipe 5 extends through an opening in the upper portion of the tube sheet 3 into the smoke-box and is suitably connected to a rearwardly-projecting neck 6 forming part of the head 7 of the deflector or header 8; the special construction of the elements 7 and 8 presenting some of the most important features of the invention. 70

The deflector 8 embodies a chamber to receive saturated steam from the dry pipe 5 via the head 7 in the manner hereinafter described and to supply it to the superheating units 9, and one or more chambers to receive 75 the superheated steam from said units and supply it, likewise by way of head 7, to feed pipes 10 which lead directly to the steam chests and thence to the cylinders. In the form represented in Fig. 2, the deflector is of 80 the two-chamber type, comprising rear and front chambers 11 and 12 for saturated and super-heated steam; but in Fig. 6, the deflector includes an additional chamber 13 to receive the steam from one group of superheating units and supply it to another group to undergo a further superheating action whereafter it passes into chamber 12, so that stage heating is thus effected. There may, of course, be more than two superheated steam 90 chambers, according to the number of stages of superheating desired.

In any case, however, the deflector is of multi-part or sectional construction, the individual hollow members or sections 14 of 95 which are substantial counterparts of one another, are arranged vertically side by side in abutting relation, and are internally partitioned to form the saturated and superheated steam chambers; the end sections having solid side plates or wings 15 fitted to them to facilitate and assist heat deflection and distribution. At their lower ends, these sections are bolted to a supporting rail or bracket 16 which is itself bolted to the smoke-box 100 wall, while their flanged upper ends are arranged flat against the bottom wall of head 7 and are fastened thereto by bolts 17 that pass through registering slots 18 and 19 formed in said flanges and in flanges or extensions on the aforesaid wall. 105

The head 7 itself rests on the sections 14

of the deflector, as will be understood, and it is further supported by means of side brackets 20 fastened to the smoke-box wall and to which it is bolted at its ends; the wing 5 plates 15 likewise being secured at opposite ends to brackets 20 and 16. This element 7 is provided internally with a partition 21 which separates its previously-mentioned neck 6 from the rest of the head and acts 10 to direct the incoming saturated steam from the dry pipe 5 into an internal passage 22 leading down toward the bottom wall of the head; such wall being formed with two sets of ports 23 and 24 separated by a partition 15 25 that constitutes a common inner wall between passage 22 and a front passage 26 hereinafter referred to. The ports 23 and 24 overlie the tops of the deflector sections 14 and register with ports 27 and 28 formed 20 therein, each section having two such ports, so that the saturated steam is thus permitted to flow into the chambers 11 of the deflector, while the superheated steam from chambers 12 can flow into the portion of the head in 25 front of partition 21 and thence into the cylinder supply pipes 10.

Communication between pipes 10 and passage 26 is controlled by a balanced valve 29, preferably in the form of an axially-bored 30 member or sleeve of slightly tapered or inverted frusto-conical shape. This valve moves up and down through upper and lower openings or seats 30 and 31 provided in partition walls within the head, and is equipped 35 with circumferential flanges 32 and 33 for coaction with the same; and it is preferably suspended by a stem 34 from a crank arm 35 attached to a horizontal rock shaft 36 which extends through a casing 37 serving as a continuation of the valve chamber, suitable guide 40 fingers 38 being provided on the valve to facilitate its movements. The exterior portion of the rock shaft 36 is journaled in a bracket 39 mounted on the outside of the boiler wall 45 2 and is provided with a second crank arm 40 suitably connected to be operated from the engineer's cab.

Due to the arrangement described, it will be apparent that superheated steam from the 50 chambers 12 of the deflector will be free to pass through the bore of the valve into the space or chamber above the valve and within the casing and will tend to press the valve ribs against their seats, thus balancing the 55 valve against the upward pressure of the steam, but cutting off communication between the supply pipes 10 and the deflector. When the valve is raised, both seats or openings will be uncovered and steam can flow to said 60 pipes from both above and below the valve; the space between the two seats emptying, and that above the upper seat re-filling as soon as the valve is again closed.

As has previously been stated, the steam 65 passes from the saturated steam chambers of

the deflector sections 14—or from the saturated steam space, as it may be regarded, provided in the deflector by said chambers—into the superheating units 9 to be converted into superheated steam. Preferably, these tubular units are of special construction, and each 70 comprises a corrugated rear portion 41 which extends through the corresponding flue 4 and is plugged at its far end, a short cylindrical front portion 42, and a sleeve 43 that 75 fits over the latter portion and extends transversely through the deflector. The tubes proper are divided horizontally by partitions 44 into upper and lower compartments 45 and 46 (Figs. 3 and 4) in a manner and for 80 a purpose similar to that shown and described in our prior Patent No. 1,597,905, granted August 31, 1926, to which reference may be had for a complete explanation; it being considered sufficient for present purposes to 85 state that the steam enters at the front end of the lower compartment 46, flows therethrough to the rear end of the compartment where it passes around the end of the partition 44 (which terminates short of the 90 plugged end of the tube, as shown in Fig. 4) and then travels through the upper compartment 45 back to the front end of the tube where it leaves.

In the two-chamber deflector represented 95 in Fig. 2, each sleeve 43 (and, of course, the tube portion 42 over which it fits) is formed with two ports 47 and 48, the ports 47 being disposed within the saturated steam chamber 11 and admitting steam therefrom into the 100 tube compartments 46, while the ports 48 are disposed in the superheated steam chamber 12 and constitute outlets for the steam from the compartments 45. Where a three-chamber deflector is employed, the sleeves 105 and enclosed tube portions have a somewhat different port arrangement including upper ports 49 that open into the first-stage superheating chamber 13 from the units and lower ports 50 that open into said units from that 110 chamber; the grouping of the ports being such that the ports 47 and 49 are formed in one set of sleeves, and the ports 50 and 48 in another set, there being three sleeves in each set in the case illustrated in which six 115 units are connected to each deflector section.

As further regards the units themselves, it will be observed that the corrugated rear portions 41 thereof have a cruciform section which may be produced in any desired way, 120 thereby increasing to a very great extent the surface area exposed to the action of the flames and gases of combustion passing through the flues and, at the same time, enlarging the passageway or space between the 125 units and the flue walls, as well as presenting a relative small volume of steam to the heat. These portions of the units are supported within the flues by means of clip brackets 51 (Fig. 3) that engage and straddle the lower 130

corrugations. The units are, of course, removable from the flues, and the sleeves 43 are detachable therefrom and from the deflector sections, whereto they are secured by 5 suitable clamping nuts or the like; and in the case of the three-chamber deflector, the sleeves may be, and preferably are, slightly tapered, their smaller ends pointing forward.

In like manner, the deflector sections 14 10 can be detached individually from the deflector for inspection and, in the event of injury, can be repaired or replaced by new ones without disturbing either the remaining sections or the deflector head. This sectional 15 formation also facilitates the construction and installation of the deflector, as well as its dismantling should occasion therefor arise.

Having thus described our invention, we 20 claim:

1. In a steam superheating system, a header provided with separate internal chambers for saturated and superheated steam which are disposed one in front of the other and are 25 devoid of direct communication; a plurality of superheating units connected to the header and adapted to receive steam from the saturated steam chamber and supply it to the superheated steam chamber after having 30 been superheated; a head mounted on the top of the header and partitioned internally to define a chamber to receive saturated steam and supply it to the saturated steam chamber of the header, and a chamber to receive super- 35 heated steam from the superheated steam chamber of the header and provided with an opening for delivering such steam for use; and a balanced valve located within said head to control the passage of steam to the super- 40 heated steam chamber thereof from the super- heated steam chamber of the header.

2. In a steam superheating system, a header provided with separate internal chambers for saturated and superheated steam which are disposed one in front of the other and are 45 devoid of direct communication; a plurality of superheating units connected to the header and adapted to receive steam from the saturated steam chamber and supply it to the

superheated steam chamber after having been 50 superheated; a head mounted on the top of the header and partitioned internally to define a chamber to receive saturated steam and supply it to the saturated steam chamber of the header, a valve chamber in controllable 55 communication with the superheated steam chamber of the header but devoid of communication with the saturated steam chamber of the head, and an outlet chamber to one side of and constantly communicating 60 with the valve chamber; and a valve in the valve chamber to control communication between the latter and said superheated steam chamber.

3. A steam superheating system, according 65 to claim 1, in which the valve is provided with a bore for constantly admitting steam from the superheated steam chamber of the header to a point above it in the head for balancing purposes, such steam exhausting 70 through the delivery opening when the valve is raised.

4. A steam superheating system, according 75 to claim 2, in which the valve has the form of a hollow, open-ended sleeve to enable steam from the superheated steam chamber of the header to pass constantly through it to a point in the valve chamber above the valve for balancing purposes, such steam exhausting 80 into and through the outlet chamber when the valve is raised.

5. A steam superheating unit, comprising a tube embodying a rear portion of cruciform section which extends the greater portion of the tube length, and a cylindrical front portion; a horizontal partition within the tube extending from the front end thereof to within a short distance of the rear end, and dividing the interior of the tube into upper and lower horizontal compartments which open 85 into each other at their rear ends; and brackets straddling the lower arms of the cruciform rear portion of the tube for supporting such portion within a boiler flue.

In testimony whereof we affix our signatures.
